UNITED STATES PATENT OFFICE

JOHN G. BOLLOCK, OF HASTINGS, NEBRASKA

SAFETY APPLIANCE

Application filed May 8, 1928. Serial No. 276,105.

This invention relates to pneumatic hammers and more particularly to a device for removably securing the tool to the barrel of the pneumatic hammer to prevent the same 5 from becoming displaced, but at the same time provide means to permit the ready attachment or detachment of the tool or set.

An object of the invention is to provide a device of this character including a spring 10 cushioning means to cushion the movements of the securing device to relieve the operator's hands of undue strain when the tool is in operation.

With the foregoing and other objects in view, which will appear as the description proceeds, the invention resides in the combination and arrangement of parts and in the details of construction hereinafter described and claimed, it being understood that changes 20 in the precise embodiment of the invention herein disclosed may be made within the scope of what is claimed, without departing from the spirit of the invention.

Referring to the drawing:

25 Figure 1 is an elevational view of a pneumatic hammer supplied with a device constructed in accordance with the invention.

Figure 2 is a longitudinal sectional view, through the housing at one end of the device.

30 Figure 3 is a sectional view taken on line 3—3 of Figure 1.

Figure 4 is a sectional view taken on line 4—4 of Figure 2.

Figure 5 is an elevational view of a modified form of the invention.

Referring to the drawing in detail, the reference character 5 designates the barrel of a pneumatic hammer and the reference character 6 designates the handle portion there- 40 of, the barrel and handle being of the usual and well known construction.

Fitted in one end of the barrel 5 is a tool 7 which is provided with a peripheral flange 8 against which the loop 9 engages, the loop 45 9 being of a diameter to fit over the head of the tool, in a manner as shown by Figure 1, with the result that rotary movement of the tool is permitted, but displacement of the tool accidentally is prevented.

50 This loop 9 is formed at the outer end of

rod 10 and is bent at right angles with respect thereto, the opposite end of the rod 10 having a head 11 that engages one end of the coiled spring 12 which is mounted within the housing 13 that in turn is secured 55 to the barrel 5 adjacent to the handle thereof.

A slot 14 is formed in the end wall of the housing 13 and receives the rod 10, through which slot the rod 10 moves, when it is desired to move the device to a position 60 to release the tool. The opposite end of the coiled spring 12 engages one wall of the housing 13 as clearly shown by Figure 2. Grooves are formed in the outer surfaces of the sides of the housing 13 adjacent to the upper edges 65 thereof and accommodate the ribs 15 that extend inwardly from the depending flanges 16 of the cover 17, defining a construction which will permit the cover 17 to be readily and easily removed or replaced, should it be 70 desired to repair or replace spring 12.

The cover 17 is held in position by means of a screw indicated at 18, to the end that accidental displacement of the cover will be prevented.

75 Straps 25 are formed integral with the housing 13 and are formed with apertured ears to receive the bolt 26 for securing the ends of the straps together. It will be seen that these straps may be moved into close engagement with the barrel 5 to hold the housing in position.

In the form of the invention as illustrated by Figure 5, the device embodies a rod 19 formed with a loop 20 at one end thereof, the loop being provided to fit over the tool with which the device is used. At the opposite end of the member 19 is a loop 21 through which the strap 22 extends, the strap 22 being provided to secure the member 19 to the handle.

I claim:

In a device of the character described, a housing, one end of the housing having a slot extending from the upper edge thereof, a 25 rod having a loop at one end fitted over the head of a tool, a head at the opposite end of the rod, a coiled spring on the rod, one end of the spring engaging the head, the opposite end of the spring engaging the housing adj- 109

cent to the slot, to normally hold the rod to the limit of one of its movements, a cover slidably mounted on the housing and having an end wall closing the slot over the rod, and means for securing the cover in position.

5 In testimony that I claim the foregoing as my own, I have hereto affixed my signature.

JOHN G. BOLLOCK.
